TYPEWRITING MACHINE

Frank P. Kuhl, New York, N. Y., assignor to Underwood Corporation, a corporation of Delaware

Application June 14, 1943, Serial No. 490,945

13 Claims. (Cl. 197—3)

This invention relates to typewriting machines and more particularly to machines of the so-called Elliott Fisher type provided with a substantially flat platen. The machine embodying the invention is particularly designed for typing on large engineering drawings on tracing cloth or on other large sheets.

The making of neat accurate lettering of attractive appearance on engineering tracings requires years of experience and draughtsmen who have training sufficient to execute properly this work are hard to find. This lettering work requires a great deal of skill and painstaking care and the lettering adds substantially to the cost of a drawing especially when a considerable amount of lettering on a sheet is necessary.

One object of the present invention is to produce a typewriting machine upon which satisfactory lettering may be efficiently applied to large engineering drawings.

Another object of the invention is to construct a typewriting machine upon which large engineering drawings may be quickly and easily placed on a platen in position for typing on any desired portion of the drawing and the required lettering applied thereto in an efficient manner with the saving of considerable time and expense as compared with hand executed lettering.

Another object of the invention is to provide a typewriting machine for typing on large engineering drawings in which the platen and type mechanism are relatively positioned and rigidly held during each typing operation so as to produce a type impression of substantially uniform opacity.

With the above and other objects in view, the invention consists in a machine embodying the novel and improved features, constructions and combinations of parts hereinafter described, and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings,

Fig. 1 is a perspective view illustrating a machine embodying the invention.

Fig. 2 is a view in side elevation of the machine, illustrating the type head, line space frame and work clamping frame tilted back away from the platen to enable a work sheet to be applied to or removed from the platen, the line space frame and the type head being shown in dot and dash lines.

Fig. 3 is an underside plan view illustrating the platen and certain associated parts, partly broken away,

Fig. 4 is a detail view in vertical section taken

through the rear portion of the platen and the parts to the rear of the platen.

Fig. 5 is a view in vertical section illustrating the forward portion of the platen and the parts ahead of the platen taken substantially on the line 5—5 of Fig. 3.

Fig. 6 is a detail view in vertical section taken through a side marginal portion of the platen and certain associated parts.

Fig. 7 is a detail exploded view illustrating the mechanism for stopping the tilting movement in an upward direction of the type head, the line space frame or carriage and the supporting frame for the line space carriage, and

Fig. 8 is a detail view in front elevation with parts in section illustrating the construction for supporting a bar adjacent the forward edge of the platen.

The typewriting machine in which the invention has been embodied, as illustrated in the drawings of this application, is a machine of the so-called Elliott Fisher or flat platen type having the same general construction except as to the platen, the mounting means for the platen and the supporting frame for supporting the line space frame and for holding the work sheets on the platen, as the machine illustrated and described in the patent to Foothorap, No. 1,904,127, dated April 18, 1933. The machine comprises a substantially flat platen, a line space frame or carriage movable forwardly and rearwardly over the platen to line space the type mechanism with relation to the platen, and a type head or type carriage mounted for letter spacing and return movement on the line space frame. The line space frame, the mechanism for actuating and controlling said frame to line space the type mechanism, the type carriage, the type mechanism, and the escapement mechanism all preferably have substantially the same construction, arrangement and mode of operation as the corresponding mechanisms illustrated and described in said Foothorap Patent No. 1,904,127.

The platen of the machine, indicated at 2 consists of the usual flat plate fixedly supported in a substantially horizontal position upon a supporting plate 4 in spaced relation to the latter plate by means of U-shaped brackets 6 bolted respectively to the platen and to said supporting plate 4. These brackets furnish sturdy rigid supports for the platen to hold the same firmly against the blows of the type as is required to give sharp clear-cut type impressions. The plate 4 may be attached to any suitable rigid supporting device such as a table or desk 8 upon which the typing operation is to be performed.

The supporting frame for supporting the line space frame or carriage and for clamping a work sheet upon the upper surface of the platen is indicated as a whole at 10. This frame com-

prises side bars 12 arranged to extend over the side margins of the platen 2 which normally supports said frame, front and rear cross bars 14 and 16 connecting the opposite ends of the side bars and an intermediate cross bar 18 also connecting said side bars. This frame extends a short distance beyond the platen at the front end of the platen and the cross bar 14 is located forwardly of the platen and in spaced relation thereto. The frame 10 extends some distance beyond the platen at the rear and the intermediate cross bar 18 is located to the rear of the platen in spaced relation thereto as shown in Fig. 4, to form a slot 19 between the rear end of the platen and said bar.

The side bars 12 of the supporting and work holding frame 10 form tracks upon which is mounted for forward and rearward movement the line space frame indicated as a whole at 20. The line space frame comprises front and rear rails 22 and 24 rigidly connected by side bars 26 and is provided with wheels or rollers such as indicated at 28 and 29 engaging the track portions 30 of the side bars 12. The line space frame carries gears 32 fixed to a horizontal shaft 33 and engaging racks 34 respectively attached to the side bars 12 of the work clamping frame. This shaft is rotated to impart line spacing movements to the line space frame. Such movements may be imparted manually to the line space frame by means of a forwardly and rearwardly extending rock shaft 36 mounted in bearings in said frame and operatively connected at its rear end with mechanism for rotating the shaft 33 which may have substantially the construction shown and described in the patent to Foothorap, No. 1,275,413, dated August 13, 1918. To the forward end of the rock shaft is fixed an arm 38 by which the shaft may be rocked manually to actuate the line space frame.

Upon the line space frame is mounted the type carriage indicated as a whole at 40. As stated above, this carriage is supported for letter spacing and return movements on the front and rear rails 22 and 24 of the line space frame and is provided with wheels or rollers 42 for engaging said rails. The type carriage is acted upon by a metallic band 44 connected at one end with the type carriage and wound about a spring drum 46.

In order to enable the line space carriage supporting the work clamping frame 10, the line space frame, and the type carriage to be swung upwardly away from the platen so that a work sheet may be applied to or removed from the platen, the supporting frame 10 is pivoted upon a horizontal axis located to the rear of the platen in spaced relation thereto and lying in a plane below the plane of the platen. In the construction shown, a horizontal shaft 48 is fixedly mounted at its ends in brackets 50 attached to the opposite sides of the supporting plate 4. As shown in Fig. 7, the respective ends of the shaft are inserted in the brackets 50 and the shaft is held from turning in the brackets by means of pins such as 53 engaging in openings 54 and 56 formed respectively in each bracket and the corresponding end portion of the shaft. In order to pivot the supporting frame upon the shaft 48, bearing brackets 58 are attached respectively to the side bars 12 of the frame and are each formed with suitably-shaped sockets 60 to receive the shaft as shown in Fig. 4. These brackets are held from disengagement from the shaft by means of retaining plates 62 attached respectively to the

brackets below the shaft as shown in this figure. The brackets 58 are formed with projections 63 and the ends of the cross bar 18 are interposed between the side bars 12 of the supporting frame 10 and said projections are secured to said side bars by screws 64.

As shown clearly in the drawings, the shaft 48 is located some distance below the plane of the platen 2 and the brackets 58 extend downwardly from the side bars of the supporting frame a distance corresponding with this difference in the vertical position of the platen and said shaft. The shaft is also located some distance to the rear of the platen.

With this construction, when the supporting frame 10 is tilted upwardly to the position shown in Fig. 2 to enable a work sheet to be applied to or removed from the platen, a relatively wide free space is opened up between the rear end of the platen and said frame and brackets 58 for the insertion or removal of the work sheet, indicated at S, the rear portion of which may be rolled up on a hollow roll R. The arrangement of the shaft 48 and the bearing brackets 58 with relation to the platen causes said brackets to swing away from the rear end of the platen upon swinging the frame 10 upwardly from closed position. When the frame is swung downwardly to locate the type carriage in working position with relation to the platen and to clamp the work sheet on the platen, said brackets 58 swing back toward the rear end of the platen; and, if a roll has been inserted in the space beneath the rear end of the platen, the brackets and cross bar 18 form an enclosure below the rear end of the platen to receive the rear marginal portion of the work sheet S.

The rolled up portion of the sheet is held in this enclosure and the sheet extends from said rolled up portion through the elongated opening or slot 19, as shown in Fig. 4.

To limit the upward swinging movement of the frame 10, stop arms 65 having openings 66 are fixed in any suitable manner to the ends of the shaft 48 projecting beyond the brackets 50, the ends of the shaft being engaged in said openings. These arms are connected by a bar 67. Upon the bar 67 are fixed the stop blocks 68 preferably of resilient material arranged to be engaged by the side bars of the supporting frame 10 when the frame is swung upwardly to limit the upward movement of the frame. The stop arms 65 preferably are adjustable about the shaft 48 to enable the stop blocks 68 to be adjusted to vary the limiting uppermost position of the frame 10. To this end, in the construction shown, each of the arms is slotted at 70 and a headed draw bolt 72 is passed loosely through an opening in the portion of the arm outside the slot and is threaded into the inner portion of the arm. The arms are fixed to the shaft by tightening the draw bolts and may be adjusted about the shaft to adjust the stop blocks upon loosening said bolts.

It is particularly important in the present machine, that the type engage the tracing held on the platen with substantially equal pressures at all points on each type face. This will give an ink impression which is substantially uniform throughout each letter or figure printed by the types and each letter will have a substantially uniform opacity throughout. To obtain this substantially uniform type impression, it is important that the platen and the type carriage shall be accurately located relatively and that the

platens and the frame 10 having the guide rails 30 for the line space carriage shall be rigidly supported during a typing operation. This is accomplished in the present machine. The platen is rigidly supported on the brackets 6 and the supporting frame 10 is itself rigidly supported by the platen to which it is clamped, the side bars of the frame resting on the work sheet lying on the upper surface of the platen. The tracing or other work sheet is thus clamped firmly against the upper surface of the platen so as further to ensure the formation of type impressions of uniform opacity.

The cross bar 14, attached to the forward ends of the side bars, is located below the side bars and in substantially the plane of the platen when the supporting frame is closed. The bar 14 is spaced from the forward end of the platen and in the space thus provided is located a supplemental bar 74 lying just to the rear of the cross bar 14 when the frame 10 is closed. This supplemental bar is also located in position to leave a slot 76 between the same and the forward end of the platen through which the work sheet passes. The bar 74 is employed as an abutment against which engages a retaining device for the forward end of the supporting frame to hold the frame securely in lowered position. The bar is mounted on the supporting plate 4 so that it may be swung forwardly out of operating position as shown in dotted lines in Fig. 5.

The bar 74 is fixed by means of screws 75 to the upper ends of spaced U-shaped brackets 78, the lower ends of which are hinged to the supporting plate 4. The lower ends of the brackets 78 are connected by a connecting bar 80 secured to the upper sides of the feet of the respective brackets by means of screws 82. Attached to the connecting bar 80 are two hinges for supporting the brackets and thereby hingedly supporting the bar 74. Each of these hinges comprises an upper member 84 fixed by means of screws 86 to the under side of the connecting bar 80, a pintle 88 and a lower hinge member 90 secured by means of screws 92 to the supporting plate 4.

In order to hold down firmly and preferably with some pressure, the forward end of the supporting and work clamping frame, a latch 94 is pivoted upon a stud 96 fixed in and projecting from the under side of the cross bar 14. This latch member is provided with a latch or retaining arm 98 having a turned back inclined or cam portion 100 and arranged to engage beneath the supplemental bar 74 as shown in Figure 5 to hold down the forward end of the frame 10. The latch lever 94 is acted upon by a coiled spring 102 which tends to retain latch arm 98 of the lever in latching position, movement of the lever under the action of the spring being limited by the engagement of a stop arm 104 on the lever with a stop pin 106 fixed in the cross bar 14.

To enable the operator readily to release the latch lever from the bar 74 so that the supporting frame 10 may be lifted to the position shown in Fig. 2, the machine is provided with a longitudinally movable latch releasing bar or rod 108. This rod is supported at one end by means of an arm 110 pivoted on a stud 112 fixed in the under side of the cross bar 14, the end of the rod being pivotally connected with the arm. The rod 108 is slidably supported at its opposite end by means of two spaced screws 114 threaded into the under side of the cross bar 14 with their heads spaced from the bar between which screws the rod 108 is slidably engaged as shown in Fig. 3.

From the under side of the rod 108 projects a pin 109 arranged to engage a forwardly projecting arm 111 on the latch lever to move the latch lever to latch releasing position. To the free end of the rod 108 is attached a button or disk 116 by which the rod may readily be manipulated.

With this construction, when the supporting and work clamping frame is swung downwardly into position to locate the line space and type carriages in operating position and to clamp a tracing or other work sheet upon the upper surface of the platen, the lower inclined face of the turned-back cam portion 100 of the latch lever 94, engages the upper outer corner of the supplemental bar 74 which then lies in the position shown in Fig. 5 and the latch arm of the latch lever is thereby pushed back against the action of the spring 102 so that further downward movement of the forward end of the frame finally carries the latch lever below the bar 74 and the latch lever is swung into position to engage the latch arm 98 beneath the bar 74 and thereby clamp the frame firmly to the platen. To release the latch from the bar 74, the operator grasps the button 116 at the right hand end of the rod 108 and moves the same to the left. This movement of the rod swings the latch lever 94 to disengage the latch arm 98 from beneath the bar 74 so that the forward end of the frame 10 may then freely be moved upwardly.

In the drawings the forward portion of the tracing or other work sheet is shown rolled up on a hollow cylinder R'. When the supporting and work clamping frame is swung into its upper position and the cross bar 74 and brackets 78 are located in the position shown in full lines in Fig. 5, said bar and brackets lie in retaining position with relation to the space between the forward end of the platen and the supporting plate 4 thereby obstructing the insertion or removal of a rolled up portion of the tracing into or from this space. The bar 74 and the brackets 78 are hinged so that they may be swung forwardly and downwardly into the dotted line position shown in Fig. 5, thereby leaving free and unobstructed this space between the forward end of the platen and the supporting plate 4. When the bar 74 and said supporting brackets are in the positions shown in dotted lines in this figure, the rolled up portion of the tracing may readily be inserted from above and in front of the platen into the space between the forward end of the platen and the plate 4. Then when the roll of tracing is in place, the bar 74 and the brackets 78 may be swung back to the position shown in full lines in Fig. 5 to retain the rolled up portion of the tracing in position.

In order to hold down the portion of a tracing above the rear margin of the platen, a strip 117 of rather stiff sheet material such as cellulose acetate is attached to the cross bar 18 and is arranged to extend forwardly from said cross bar over the rear of the platen, as shown in Fig. 4.

For the purpose of locating the forward portion of the supporting frame 10 laterally with relation to the platen, brackets 76a are attached respectively to the undersides of the side bars 12 of said frame and are formed with downwardly extending portions 78a arranged to be located in engagement with the ends of bar 74 or in close proximity thereto when the frame 10 is closed.

With the above construction, both the platen and the rails carrying the printing mechanism are securely fastened together so that they are

located and held in their proper relative positions in a reliable manner during a typing operation and are both firmly and rigidly supported at that time. This enables the upper surface of the platen and the faces of the types, when the types are in striking position, to be maintained exactly in parallel relation to produce type impressions of uniform opacity.

The rear cross bar 16 of the supporting frame 10 is formed with upwardly extending projections 118 located just outside the side bars 12 to engage portions of the line space frame and thereby limit the rearward movement of said frame on said side bars.

Fig. 6 shows the manner in which the work sheet S is clamped on the platen by the supporting and clamping frame 10. As shown in this figure, the work sheet extends laterally from beneath the side bars 12 of the work clamping frame under the side bars 26 of the line space frame. The plate 120 shown in this figure is one of the usual small plates attached to the line space frame and extending beneath the side bars of the work clamping frame to prevent the line space frame from being moved upwardly with relation to the work clamping frame except when the inner portions of these plates are located opposite recesses in the side bars of the supporting frame 10.

With the above construction, large tracings and other large work sheets may be lettered or typed with letters each having a substantially uniform ink deposition and therefore a substantially uniform opacity throughout and the lettering may be very quickly and efficiently performed. Before inserting a tracing or other work sheet in the machine, the line space frame with the type carriage is moved to its limiting rearward position on the supporting frame 10, the latch lever 94 is manipulated to disengage the same from the under side of the bar 14, and the supporting frame is swung upwardly substantially to the position shown in Fig. 2, until the movement of the frame is stopped by the engagement of the side bars 12 on the frame with the stop blocks 68. The bar 14 with the supporting brackets 78 is then swung forwardly to the position shown in dotted lines in Fig. 5. The swinging of the supporting and clamping frame 10 upwardly leaves a free and unobstructed space at the rear of and beneath the rear end of the platen so that a roll of the tracing S may be inserted beneath the platen from above and the rear and the tracing may be brought forward over the platen. The swinging of the bar 14 forwardly to the position shown in Fig. 2, and in dotted lines in Fig. 5, leaves a free open space at the front of the platen and beneath the forward end thereof in which may be inserted a roll of the tracing S rolled up on the cylinder R'. When the tracing is located on the platen in position for the typing of the data at the desired point thereon, the bar 14 is swung back to the position shown in Fig. 1 and in full lines in Fig. 5, and the supporting and clamping frame 10 is swung down to the position shown in these figures to locate the type carriage in typing position with relation to the platen and to clamp the tracing firmly upon the upper surface of the platen. During the last part of the downward movement of the frame 10, the latch arm 98 of the latch lever 94 is pushed back by the engagement of the inclined extension 100 with the bar 14 and when the frame has been depressed to clamp the tracing firmly on the work sheet, the latch lever is actuated to engage the latch arm

98 beneath the bar 14 to hold the frame 10 securely and rigidly in operating position.

The spaces beyond the side edges of the platen are substantially unobstructed below the plane 5 of the platen. If the tracing or other work sheet to be typed is wider than the platen, the tracing may extend laterally from the platen underneath the side bars 26 of the line space frame as shown in Figs. 1 and 6. The rolls of the tracing at the 10 forward and rear margins of the platen may extend outwardly any distance from beneath said forward and rear margins.

The parts are preferably constructed and arranged so that the clamping frame 10 engages the tracing or other work sheet and its downward pivotal movement is stayed before the latch arm 98 engages beneath the bar 14. Then the forward end of the frame is forced down slightly until said latch arm engages beneath the bar 14, the side members 12 of said frame flexing slightly during this depression of the forward end of the frame. The latch will thereafter clamp the forward end of the frame in depressed position against the resilience of the side members and the work sheet will be clamped firmly on the upper surface of the platen.

The above described construction not only enables a tracing or other work sheet to be quickly and easily placed on the platen in position for typing but also to be very readily shifted, after being placed in the machine, to change the typing point. Thus the tracing may be shifted laterally by sliding the same bodily across the platen. The tracing may be shifted forwardly or rearwardly by rolling up and unrolling the rolls at the forward and rear margins of the tracing as required.

Having explained the nature and object of the invention, and having specifically described a construction embodying the invention in its preferred form,

What is claimed is:

1. A typewriting machine comprising a substantially flat fixed platen; a supporting frame movable toward and from the platen and arranged to clamp work sheets upon the upper surface of the platen, a carriage frame supported on said supporting frame and movable thereon in opposite directions over the platen, a carriage mounted 45 on said carriage frame for movement in opposite directions transverse to the directions of movement of said carriage frame, printing mechanism carried by the carriage, means for pivotally mounting the supporting frame to swing on a horizontal axis spaced from one edge of the platen and at a distance below the plane thereof such that an unobstructed opening of considerable size beyond said edge is provided for the insertion of a work sheet when the supporting frame is in 50 open position, means for clamping the latter frame to hold the frame rigidly to the platen and to clamp the work sheet down firmly against the platen and means for rigidly supporting the platen to leave two opposite edges unobstructed for the full dimension of the platen for the extension of a work sheet of greater dimension than the platen beyond said edges into the space below the platen and to leave two other opposite edges unobstructed for the full dimension of the platen 55 for the extension of a work sheet of greater dimension than the platen beyond said edges in the direction of the plane of the platen.
2. A typewriting machine comprising a supporting plate; a substantially flat fixed platen rigidly mounted on said supporting plate in spaced 75

substantially parallel relation thereto, a supporting frame, a carriage supported on said supporting frame and movable thereon back and forth over the platen, a second carriage mounted on said first carriage for movement in opposite directions, printing mechanism carried by the latter carriage, means for pivotally mounting the supporting frame to swing on a horizontal axis spaced from one edge of the platen and located at a distance below the plane of the platen such that an unobstructed opening of considerable size is provided at one edge of the platen and between the same and the supporting plate for insertion of a work sheet when the frame is in open position, means for clamping the opposite part of the frame with relation to the platen to connect rigidly the platen and said frame and to hold the frame down firmly against the work sheet and means for rigidly supporting the platen to leave two opposite edges unobstructed for the full dimension of the platen for the extension of a work sheet of greater dimension than the platen beyond said edges into the space below the platen and to leave two other opposite edges unobstructed for the full dimension of the platen for the extension of a work sheet of greater dimension than the platen beyond said edges in the direction of the plane of the platen.

3. A typewriting machine comprising a support, a substantially flat platen fixedly mounted on said support in spaced relation thereto, a vertically movable guide frame, a carriage supported and guided on said guide frame for movement in opposite directions over the platen, a type carriage mounted on said first carriage for movement in opposite directions transverse to the directions of movement of said first carriage, type mechanisms carried by said type carriage, means for pivotally supporting the guide frame to swing on a horizontal axis spaced from one margin of the platen and below the plane of the platen whereby an unobstructed opening of considerable size is provided between said margin and the frame for the insertion of a work sheet when the frame is in open position, said means including hinge members fixed to the guide frame and nearly enclosing the space between the support and the platen at one or more points along said margin of the platen to hold a roll of the work sheet therein when the frame is closed and means for rigidly supporting the platen to leave two opposite edges unobstructed for the full dimension of the platen for the extension of a work sheet of greater dimension than the platen beyond said edges into the space below the platen and to leave two other opposite edges unobstructed for the full dimension of the platen for the extension of a work sheet of greater dimension than the platen beyond said edges in the direction of the plane of the platen.

4. A typewriting machine comprising a substantially flat fixed platen, a supporting frame normally supported by the platen and movable toward and from the platen, a carriage mounted on said frame and movable thereon in opposite directions over the platen, a printing carriage supported on said first carriage for movement over the platen in directions transverse to the directions of movement of said first carriage, printing mechanism supported on the latter carriage, means for pivotally mounting the frame to swing on a horizontal axis adjacent one edge of the platen, a transverse bar at the opposite edge of the platen and normally located in substantially the plane of the platen and spaced from the ad-

jacent edge thereof to leave a slot for the passage of the work sheet and a clamping device for clamping a part of said frame remote from its axis to said transverse bar to hold the frame securely and rigidly in printing position.

5. A typewriting machine comprising a substantially flat rigid platen, a vertically movable frame normally supported upon the upper surface of the platen and arranged to clamp work sheets thereon, a carriage mounted on said frame and reciprocatable thereon over the platen, a type carriage supported on said first carriage for movement in directions substantially perpendicular to the directions of movement of said first carriage, type mechanisms carried by the latter carriage, means for pivotally supporting the frame to swing on a horizontal axis adjacent one end of the platen, a transverse bar at the opposite end of the platen and normally located in substantially the plane of the platen and spaced from the adjacent end of the platen to leave a slot for the passage of the work sheet, means for supporting said transverse bar for movement away from the adjacent end of the platen to leave a clear space for the insertion and removal of a work sheet and an attaching device for attaching that part of said frame adjacent said transverse bar to said bar to hold the frame rigidly with relation to the platen.

6. A typewriting machine comprising a platen support, a substantially flat platen fixed to said support in spaced relation thereto, a vertically movable supporting structure normally supported by the upper surface of the platen, a frame movable back and forth on said structure, a carriage supported on said frame for movement in opposite directions, printing mechanism carried by the carriage, means for pivotally supporting said structure to swing on a horizontal axis relatively adjacent one edge of the platen, a transverse bar at the opposite edge of the platen normally located in substantially the plane of the platen and spaced from the adjacent edge of the platen to leave a slot for the passage of the work sheet, a clamping device for clamping the part of said structure adjacent said transverse bar to said bar to hold the structure firmly and securely with relation to the platen and means for mounting said bar nearly enclosing, at one or more points along the length of the bar, the space between the platen and said support at the adjacent edge of the platen to hold a roll of the work sheet therein.

7. A typewriting machine comprising a support, a substantially flat fixed platen mounted in spaced relation to said support, a vertically movable track frame normally supported by the platen and having guide tracks thereon, a second frame mounted on said tracks and movable thereon back and forth over the platen, a carriage supported on said second frame for movement in directions transverse to the directions of movement of the second frame, printing mechanism supported on the carriage, means for pivotally supporting the track frame to swing on a horizontal axis adjacent one margin of the platen, a transverse bar at the opposite margin of the platen normally located in substantially the plane of the platen and spaced from the adjacent margin of the platen to leave a slot for the passage of the work sheet, means for supporting said bar for movement away from the adjacent margin of the platen to leave a clear space inside of and below the bar for the insertion of the work sheet, said means being arranged nearly to enclose, at

one or more points along the length of the bar, the space between the platen and said support at the adjacent margin of the platen when the bar is in operating position to hold a roll of the work sheet therein and an attaching device for firmly securing that part of said frame adjacent to said transverse bar to said bar to hold the frame firmly and rigidly with relation to the platen.

8. A typewriting machine comprising a substantially flat fixed platen, a vertically movable structure normally supported by the platen and having spaced side bars, a frame mounted on said structure and movable thereon in opposite directions over the platen, a type carriage mounted on said frame for movement in directions substantially perpendicular to the directions of movement of said frame, type mechanisms supported on the carriage, said structure having a cross bar connecting the side bars adjacent one edge of the platen and located substantially in the plane of the platen when the structure is closed but leaving a slot between the adjacent edge of the platen and said bar for the passage of a work sheet, means for pivotally supporting said structure to swing on a horizontal axis located in spaced relation to the adjacent edge of the platen and in a plane at a distance below the same such that an unobstructed opening of considerable size is provided between the platen and said bar when said structure is open for the insertion and removal of a work sheet, means for attaching said structure rigidly with relation to the platen to furnish a rigid support for said frame and the type carriage and to hold a work sheet securely on the platen and means for rigidly supporting the platen to leave two opposite edges unobstructed for the full dimension of the platen for the extension of a work sheet of greater dimension than the platen beyond said edges into the space below the platen and to leave two other opposite edges unobstructed for the full dimension of the platen for the extension of a work sheet of greater dimension than the platen beyond said edges in the direction of the plane of the platen.

9. A typewriting machine comprising a substantially flat fixed platen, a vertically movable supporting frame normally supported upon the upper surface of the platen, a carriage mounted on said supporting frame for movement in opposite directions over the platen, a type carriage supported on said first carriage for movement over the platen in opposite directions transverse to the movements of said first carriage, means for supporting said frame for movement to a position to leave open spaces of substantial size at opposite edges of said platen for the insertion of the portions of a work sheet extending beyond the platen and means for clamping a portion of said frame rigidly with relation to the platen in position to provide a firm, rigid support for said type carriage to locate each type face in precise parallel relation to the upper surface of the platen when the type is in striking position and to cause the frame to exert a yielding pressure on the work sheet.

10. A typewriting machine comprising a fixed flat platen, a writing mechanism cooperating therewith, means normally supported on the platen for supporting the writing mechanism for movement over the platen to letter space and to

line space, mechanism for mounting said supporting means for movement away from the platen to a position to leave the front, rear and sides of the platen unobstructed for the free insertion and removal of a work sheet extending beyond the same and means for clamping said supporting means rigidly with relation to the platen in position to give a firm, rigid support for the writing mechanism to locate each type

5 face in precise parallel relation to the upper surface of the platen when the type is in striking position and to cause said supporting means to exert a yielding pressure on a work sheet resting on the platen.

10 15 20 25 30 35 40 45 50 55 60 65 70 11. A typewriting machine comprising a substantially flat fixed platen, a frame movable back and forth over the platen, a type carriage movable in opposite directions on said frame, a support upon which said frame is movably mounted, arranged to clamp the paper to the upper surface of the platen, means for mounting said support for movement toward and away from the platen respectively to leave margins of the platen free for the insertion and removal of a work sheet extending beyond the platen and means for attaching said support rigidly with relation to the platen in position to clamp the work sheet thereto and to locate the type impression face of each type, when in work engaging position, substantially parallel with the upper surface of the platen and to cause said support to exert a yielding pressure on a work sheet resting on the platen.

12. A typewriting machine comprising a substantially flat platen, a vertically movable supporting frame normally supported upon the upper surface of the platen and constructed and arranged so that two opposite margins of the platen are unobstructed for the full dimension of the platen for the extension of a work sheet of greater dimension than the platen over the edge and into a plane below the plane of the platen and that two other margins are unobstructed for the extension of a work sheet of greater dimension than the platen outwardly beyond the corresponding edges in the direction of the plane of the platen, a carriage mounted on said supporting frame for movement in opposite directions over the platen, a type carriage supported on said first carriage for movement over the platen in opposite directions transverse to the movements of said first carriage, means for supporting the frame for vertical movement with relation to the platen to permit the insertion and removal of a work sheet and means for clamping said frame to the platen.

13. A typewriting machine comprising a substantially flat platen, a vertically movable supporting frame normally supported upon the upper surface of the platen and constructed and arranged so that the forward and rear margins of the platen are unobstructed for the full dimension of the platen for the extension of a work sheet longer than the platen over the edges and into positions below the plane of the platen and that the two side margins of the platen are unobstructed for the extension of a work sheet wider than the platen outwardly beyond the corresponding edges of the platen in the direction of the plane of the platen and means for supporting the frame for vertical movement with relation to the platen to permit the insertion and removal of a work sheet.
